UNITED STATES PATENT OFFICE.

EDWIN D. MCLEAN, OF MARISSA, ILLINOIS.

BOILER-CLEANING DEVICE.

1,158,948.

Patented Nov. 2, 1915.

Application filed July 19, 1915. Serial No. 40,653.

To all whom it may concern:

Be it known that I, EDWIN D. MCLEAN, a citizen of the United States of America, a resident of Marissa, in the county of St. Clair, State of Illinois, have invented certain new and useful Improvements in Boiler-Cleaning Devices, of which the following is a full, clear, and exact description, reference being had to the accompanying drawings, forming a part of this specification.

My invention relates to a device for cleaning the interior surfaces of steam boilers, the invention having for its object to provide a simple and efficient means in which a hose nozzle, extending into the boiler, is adjustably fitted to provide for longitudinal and rotative movement of the nozzle in order that a stream of water may be directed against all portions of the inner wall of the boiler shell and the exterior surface of the boiler tubes; the said means serving to maintain the hose nozzle firmly in adjusted positions in consequence of the force of water delivered through the hose nozzle.

The salient features of merit in my boiler cleaning device are the construction and arrangement of parts providing for the efficient operation of the device from the exterior of a boiler, and the provision of means whereby the operator can determine and regulate the direction of discharge of the stream from the hose nozzle in applying such stream to the various surfaces to be cleaned.

Figure I is a longitudinal section of a portion of a steam boiler with my cleaning device applied thereto, the cleaning device being shown partly in elevation and partly in section. Fig. II is a view similar to Fig. I showing the cleaning elements mounted upon and in the boiler as they appear when the cleaning device is not in service. Fig. III is an enlarged top view of the cleaning device and fragments of the boiler, the hose connection being shown in cross section taken on line III-III, Fig. I.

In the drawings: A designates the shell of a steam boiler and B the tubes within said shell. A hole is formed in the boiler shell A, preferably at or near the longitudinal center of the space occupied by the tubes B, and an internally threaded boss 1 is secured to the shell at the location of this hole.

2 designates a tubular column, the lower portion of which is threaded and extends

through said boss 1, preferably to such degree that the column is located partly exterior of the boiler shell and partly interior thereof as shown in the drawings. The column 2 has an enlarged cup-shaped upper end member 3 provided with an internal screw thread 4.

5 designates a nozzle slidably and rotatably fitted in the tubular column 2. This nozzle has a curved spout 6, and is preferably of sufficient length to reach from the upper or outer end of the column 2 to a point near the portion of the wall of the boiler shell diametrically opposite to and farthest from the portion of the shell to which the column 2 is attached. The said nozzle is of such material and strength that it will resist the lateral strain exerted on it by the water passing through the nozzle and curved at its spout 6. The nozzle 5 is provided at its upper or outer end with a screw thread to provide for the application of a hose connection thereto.

7 designates a hose through which water is delivered to the nozzle 5. In the end of this hose applied to the nozzle is an inner coupling member 8 which seats against the outer end of the nozzle 5, the said member being held in place by an outer coupling member 9 which internally threaded and engages the threaded outer end of the nozzle. The outer coupling member 9 is held from turning on the nozzle by a lock nut 10.

11 designates a handle having a collar 90 member which surrounds the nozzle and is held from movement thereon by a set screw 13. The handle has conjoined to it a pointer 12 and said handle is intended to be so secured to the nozzle that the pointer will extend in the same direction as the spout of the nozzle to thereby indicate the direction in which a stream of water is discharged from the nozzle, this being important owing to the spout of the nozzle being hidden from view within the boiler.

The operation of my boiler cleaning device is as follows: Water under pressure is delivered from the hose 7 into the nozzle 5 and escapes through the curved spout in a stream of sufficient force to dislodge sediment and loose scale from any surface in the boiler against which the stream is directed, the efficiency of the cleaning action being limited only according to the degree 105 of pressure against the water. During the operation of the device the nozzle 5 is held

in positions to which it is adjusted due to the force of the water escaping from the nozzle pressing the nozzle laterally in the tubular column 2, with resultant binding action between these parts. The nozzle, therefore, remains fixed until it is readjusted.

In using the device the operator grasps the handle 11 attached to the nozzle and preferably moves the nozzle to position its 10 spout above the tubes within the boiler shell. He then turns the nozzle from side to side or in a complete circle, thereby causing the stream of water escaping from the nozzle to clean the upper portion of the boiler shell 15 at the sides and ends and the top surfaces of the uppermost tubes. The nozzle is then turned so that the pointer 12 is directed longitudinally of the boiler and moved downwardly between the central rows of tubes. 20 The operator exerts a turning strain upon the handle as he moves the nozzle downwardly and therefore turns the spout of the nozzle between the topmost tubes and those in the next lowermost row as soon as the 25 spout has passed beneath the former. The pointer will then indicate that the nozzle spout is directed laterally and upon turning the nozzle to and fro or in a complete circle the tubes above and below the nozzle 30 spout and the portions of the shell wall opposite said tubes and at the ends of the boiler. This procedure is continued between each successive pair of rows of tubes and finally to a point near the bottom of the 35 boiler shell.

My cleaning device is preferably used immediately after draining a boiler and while the scale and sediment are in a soft condition so that they may be more easily separated 40 from the surfaces to which they are adhered. The sediment and scale may be readily removed from the boiler by uncovering the lower manhole by removal of the lower manhead of the boiler.

45 When the operation of my device is completed the hose connections are separated from the nozzle 5, the locknut 10 is also removed, the handle 11 is taken from the nozzle, and the locknut 10 is again replaced. 50 The nozzle may then be lowered to position the locknut in the cup shaped upper end 3 of the tubular column 2 so that it will serve

to support the nozzle suspended in the boiler. The cap 14 is then applied to the upper end of the column 2 and forms a steam 55 tight closure therefor.

While I have described my device as used in cleaning steam boilers having tubes therein, it is obvious that it may be used also for cleaning other kinds of steam boilers or 60 tanks.

I claim:—

1. The combination with a steam boiler shell, of a tubular member secured to said shell, and a nozzle movable both rotatably 65 and longitudinally in said tubular member.

2. The combination with a steam boiler shell, of a tubular member secured to said shell, and a nozzle movable both rotatably and longitudinally in said tubular member, 70 the said nozzle having a curved spout providing for the discharge of water therefrom at an angle to the axis of the nozzle.

3. The combination with a steam boiler shell, of a tubular member secured to said 75 shell, and a nozzle rotatable and slidably longitudinally in said tubular member, the said nozzle having a curved spout, and means associated with said nozzle exteriorly of said boiler shell for adjusting said nozzle. 80

4. The combination with a steam boiler shell, of a tubular member secured to said shell, and a nozzle slidably and rotatably arranged in said tubular member, the said nozzle having a curved spout, means associated with said nozzle exteriorly of said boiler shell for adjusting said nozzle, and means carried by said nozzle for indicating the direction in which a stream is discharged from said spout. 90

5. The combination with a steam boiler shell, of a tubular member secured to said shell, and a nozzle slidably and rotatably arranged in said tubular member, the said nozzle having a curved spout, means associated with said nozzle exteriorly of said boiler shell for adjusting said nozzle, and a handle secured to said nozzle exteriorly of said boiler shell, the said handle being provided with a pointer for indicating the direction in which a stream is discharged from 95 said spout. 100

EDWIN D. McLEAN.
